(57) **CLAIM**

The ornamental design for a hydroponics growing container,
as shown and described.

DESCRIPTION

FIG. 1 is a perspective view of a hydroponics growing container showing my new design.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIGS. 1, 6, and 7 are included for the
purpose of showing portions of the hydroponics growing
container that form no part of the claimed design.
